UNITED STATES PATENT OFFICE.

ORNAN A. HONSINGER, OF TACOMA, WASHINGTON.

FOLDING DAVENPORT-BED.

1,349,883.

Specification of Letters Patent. Patented Aug. 17, 1920.

Application filed May 11, 1915, Serial No. 27,295. Renewed November 3, 1919. Serial No. 335,472.

To all whom it may concern:

Be it known that I, ORNAN A. HONSINGER, a citizen of the United States, and resident of Tacoma, in the county of Pierce and State 5 of Washington, have invented certain new and useful Improvements in Folding Davenport-Beds, of which the following is a specification.

My invention relates to davenports which 10 contain folding beds and comprises certain novel structures and combinations thereof which will be hereinafter described and particularly pointed out in the claims.

The object of my invention is to provide 15 an improved structure of the mechanism by which the folding bed is handled, and also to improve the structure of the divan proper. Further objects of my invention may be ascertained by a study of the following description and claims, said claims also defining 20 the scope of my invention.

In the accompanying drawing I have shown my invention in the form of construction, which is now preferred by me.

25 Figure 1 is a plan view of my device with the bed in open position, the central portions being cut away and the bed fabric being omitted at one end.

Fig. 2 is a transverse sectional elevation 30 through the parts in closed position.

Fig. 3 is a transverse sectional elevation showing the bed opened out.

Fig. 4 is a detail showing the manner of 35 operating the legs by which the outer bed section is supported.

I have herein shown my invention as embodied in a davenport, although it is evident that the folding bed structure shown may be incorporated with a couch. I do not therefore wish it understood that my invention 40 is in any way limited to a davenport, as it is intended for application to couches as well. I will however, describe it in connection with a davenport as shown.

45 The main frame 1 as herein shown consists of the main frame structure of the davenport. The folding bed structure is composed of a plurality of sections hinged so as to fold and stow beneath the seat 11 when 50 folded.

The bed frame structure 2, is composed of three sections 20, 21 and 22, the central section 21 being short and extending vertically when the parts are folded. The back or inner section 20 is supported at each end by 55 two or more links 3 and 32, these links be-

ing pivoted respectively at 31 and 34 upon the main frame 1 and being pivoted at their other ends, 30 and 33, to the bed frame section 20. In the folded position of the parts, 60 links 3 and 32 depend from their fixed pivots and support the inner, or back bed section, 20, close above the floor. In the open or unfolded position of the bed, these supporting links extend upwardly from their fixed 65 pivots, as is shown in Fig. 3, and preferably have a slight backward inclination.

A link 4, pivoted at 40 to the main frame at each end of the bed, is also pivoted at 41 to the central bed section 21. This link extends beyond the pivot 41 and is connected at 42 to link 43, by which the leg for supporting the outer bed section is controlled. The link 4 has an arm 44 projecting laterally, adjacent its fixed pivot 40, this projection being toward the side which is inward 70 when the parts are in folded position and outward when the parts are in open position.

A locking link 46, is pivoted a short distance inward from one end, to the arm 44 by pin 45 and at its other end is provided with a slot 47, through which passes pin 35, carried by the bed supporting link 32. This forms a sliding connection with said link, 80 limited in amount by the length of the slot. The other end of this link projects beyond its pivot connection with the link 4 and is pivoted at 48 to the outer edge of the seat frame 11. When the bed is in open position, 85 the under surface of link 46 contacts with the pivot 40 of link 4, notch 460 in the link 46 engaging pivot pin 40, thereby limiting its movement in one direction.

I have provided two springs 37, designed 90 to be under tension when the bed is folded and by their pull to assist the starting of the bed-opening movement. These springs 37, are shown as coiled springs and have one end fixed at 38 upon the main frame. 100 The connection of these springs with the bed frame and their adjustment is such that they exert no pull thereon, excepting during a certain portion of the opening and closing movement while near to the closed 105 position of these parts. This is done by interposing a link 36, between the spring and the anchorage for its other end. As herein shown, this anchorage consists of the pivot 31 upon which the link 3 swings. The 110 link 3 has a pin 39, projecting into the path of swing of the link 36, whereby when

the bed is in folded position, as is shown in Fig. 2, the spring 37 is placed under tension, this tension acting to swing the bed sections toward their open position. Before 5 reaching the open position of the bed, the link 36 swings into line with the spring, after which it exerts no more effort upon the bed.

The rear edge of the seat, or the outer 10 edge of the outer bed section, as the case may be, has pivoted thereto, near each end, a leg 5, this leg projecting a short distance above its pivot 50 and having pivot connection with a link 51, which extends diagonally across the corner of the bed frame and has its other end bent upward and pivoted to the end of the link 43. This link 43 is provided with a slot, shown by dotted lines at 54 in Fig. 3, through which extends 15 a pin 53, carried by the bed section 22. When the bed is open pin 53 contacts with the outer end of this slot and this link then acts to restrain the bar 4 from swinging backward, or into bed closing position until 20 the outer bed section is raised. It therefore acts as a lock to prevent accidental closing movement. When the bed is swung into closed position, the legs 5 are automatically swung upward into position substantially 25 parallel with the bed frame. The seat frame 11 has its rear edge connected with the outer section of the seat frame by a bar 12 at each end thereof. Braces 13 connect bar 12 and the seat frame.

30 The davenport back 6 is supported from the frame 1 by two sets of links, 7 and 72, the former engaging the lower part of the back and the latter the upper part. The pivot connections of the links with the 35 frame are farther separated than their connection with the back. In consequence of this and of the choice of location of the pivot points, together with the length of the links, one or the other set of the links 40 will hold the back in either of its extreme positions. In effect they form a double toggle joint, resisting a downward force when in the open position, and an upward force when in the closed position.

45 The upper ends of the upper links 72 are pivoted at 73 to the frame and their lower ends to the back. Stops 74 prevent their swing back beyond the position shown. In the normal or closed position of the davenport, the links 72 are substantially in line 50 with the back, being slightly inclined from a vertical. Because of this an upward lift upon the back will produce an end thrust upon the links 72, and this will not swing it forward, as this forms one toggle joint.

55 The lower links 7, are pivoted by their lower ends to the frame at 70 and by their upper ends to the back at 71. In the normal or closed position of the davenport the 60 lower links are inclined well forward from

the vertical. The lower edge of the back projects over the rear edge of the seat, and therefore prevents raising of the seat until the back is swung out of the way.

The top of the back may swing freely forward from the closed position. When it is swung forward the back is raised somewhat. This action swings the lower links backward until they come into a vertical position, or just past this; that is, they come 75 into substantial alinement with the back. The back may be held in this position by frictional engagement with the links 7 at 71 or by any other suitable means. These links act to hold the back in this position until 80 the bottom edge is pulled forward. The back is thus held rearwardly of and above its normal position by the second toggle joint while the bed is open.

The back is carried by the lower links at 85 a point well forward of its center of gravity. The resulting effect is for the upper end of the back to swing backward. The movable pivot of the link 72 is back of a line from the fixed pivot 73 through the 90 front lower edge of the back, the point where an upward force would be applied, when the back is in closed position. The back will not swing forward under the influence of an upward force along the line 95 described or along any line forward of this line, and stops 74 limit its backward swing. It is therefore securely locked, as by a toggle joint, against moving by an upward force applied at its lower edge. The toggle 100 may be broken, and the back swung upward only by a forward pull on the upper edge of the back.

The central sections 21 of the bed frame are connected by a strut 8, which consists 105 of a tube offset at each end so as to drop its central portion beneath the bed fabric, and having a pivotal connection with the section 21. The purpose of this strut is to hold the central portion of the ends of the bed frame 110 apart.

With the parts in folded position, as shown in Fig. 2, to open the bed the upper part of the back is pulled forward. This 115 swings the back upon the links 72 and the upward pull given by these links causes the lower edge of the back to swing upward and backward upon the links 7, thus releasing the rear edge of the seat. The rear edge of the seat may then be raised and swung forward. This causes the folded bed frame to swing upon the bars 4, the outer or front section 22, swinging with the seat and the inner section 20 swinging backward and then upward, until the parts reach the position shown in Fig. 3.

Having thus described my invention what I claim as new, and desire to secure by Letters Patent of the United States of America, is:

1. In a davenport bed, a frame, a seat mounted to swing upward and forward in opening, a back, and links pivoted to the top and bottom of the back to swing the lower edge of the back forwardly over the rear edge of the seat, and the upper links into substantial alinement with the back when the latter is in closed position, and a stop limiting the backward swing of the upper edge of the back, the pivot point of the upper links upon the back being rearwardly of a line drawn through the pivot of said link upon the frame and the point of contact of the back and seat, the bed being in closed position. 70
2. In a folding davenport, a frame, a back and back supports comprising links pivoted thereto at top and bottom and to the frame, the upper links, when the back is in closed position, extending upwardly from and in substantial alinement with the back and swinging forwardly and upwardly when the back is swung into open position, the lower links extending downwardly from and in substantial alinement with the back when the back is in open position and swinging downwardly and forwardly when the back is swung into closed position. 75
3. In a davenport bed, a main or casing frame, a back and a support therefor comprising links pivoted to the frame and to the upper and lower parts of the back, the upper end of the upper links being pivoted upon the frame, and their lower ends being pivoted to the back at such a point that, when the back is in normal or bed-closed position, the lower pivot lies rearwardly of a line including the upper pivot and the lower front edge of the back. 80
4. A folding davenport comprising a frame, a back and links connecting the top and bottom of the back with the frame, the pivot points upon the frame being more widely separated than those upon the back to bring the upper link into alinement with the back when the back is down and the lower link into alinement with the back when the back is up. 85
5. In a folding davenport, in combination, a main or casing frame, a seat, a back swinging upwardly in opening, and extending over the rear edge of the seat when these parts are in closed position, links pivoted by their upper end to the frame, and by their lower end to the upper part of the back, said lower pivot being rearwardly, when the back is in closed position, of a line including the upper pivot and the point of contact between back and seat, means limiting the backward swing of the upper part of the back, and supplemental guiding supports for the back. 90
6. In a folding davenport, in combination, a main or casing frame, a seat having its back swinging upwardly in opening and extending over the rear edge of the seat when these parts are in closed position to thereby lock the seat, links pivoted by their upper end to the frame and by their lower end to the upper part of the back to swing it forwardly and upwardly, said links extending substantially in the plane of the back when the latter is in closed or normal position, stops limiting the backward movement of the upper part of the back, and supplemental guiding supports for the back. 95
7. In a folding davenport, in combination, a main casing frame, a seat having its rear edge swinging upward in opening, a back extending over the rear edge of the seat when the davenport is closed to thereby lock its seat in closed position, links pivoted by their upper end to the frame and by their lower end to the upper part of the back, to swing it forwardly and upwardly, said links extending substantially in the plane of the back when the latter is in closed or normal position, and links pivoted to the lower edge of the back, and when the back is in closed position, extending downwardly and to the rear and pivoted upon the main frame. 100
8. In a folding davenport, in combination, a main frame, a seat, a bed structure adapted to be folded under the seat, the seat being mounted to swing its rear edge upward and forward to bring the bed structure into position for use, a back, supporting and guiding connection for the back from the main frame, comprising links pivoted by their upper ends to the frame and by their lower ends to the upper part of the back and other links pivoted to the frame and to the lower edge of the back, the upper links extending substantially in alinement with the back when the back is in closed position and the lower links extending downward and backward from the back for a like position of the back. 105
9. In a folding davenport, in combination, a main frame, a seat, a bed structure adapted to be folded under the seat, the seat being mounted to swing its rear edge upward and forward to bring the bed structure into position for use, a back, a support therefor maintaining the back with its lower edge projecting over the rear edge of the seat to lock the latter when the parts are in closed position, said back supports comprising links pivoted to the main frame and to the upper part of the back and extending substantially in the plane of the back when the back is in closed position, the upper ends of said links being that which is connected with the main frame, whereby the upper part of the back is controlled to swing forward and upward from its normal position. 110
10. In a folding davenport, in combination, a main frame, a seat, a bed structure 115
- 120
- 125
- 130

- adapted to be folded under the seat, the seat being mounted to swing its rear edge upward and forward to bring the bed structure into position for use, a back normally 5 extending over the seat edge and holding the seat down, short links pivoted by their upper ends to the main frame and by their lower ends to the upper part of the back and extending substantially in the plane of 10 the back when the back is in closed position, whereby they will resist upward movement of the back, links pivoted by one end to the lower part of the back and having their other ends pivoted below and rearwardly 15 thereof, whereby the back will be moved bodily upwardly and be turned about a longitudinal axis to swing the lower edge backward to bring the lower links into alignment with the back.
- 20 11. In a folding davenport, in combination, a main frame, a seat, a bed structure adapted to be folded under the seat, the seat being mounted to swing its rear edge upward and forward to bring the bed structure into position for use, a back normally 25 extending over the rear edge of the seat, links pivoted by one end to the main frame and by their other end to the upper part of the back, and extending substantially in 30 alignment with the back when the back is in closed position, whereby they may resist upward movement of the seat, links pivoted by one end to the lower part of the back and extending rearwardly when the back 35 is in closed position, the rear ends being pivoted upon the main frame, said lower links extending into substantial alignment with

the back when the bed is opened to thereby support the back.

12. In a folding davenport, a frame, a 40 back mounted to swing into open or closed position, and back supports comprising upper and lower links pivoted to the frame and to the back, the upper links being in substantial alinement with the back in the 45 closed position to resist an upward effort, and the lower links being in substantial alinement with the back in the open position to resist a downward effort.

13. In a folding davenport, a frame, a 50 back mounted to swing into open or closed position, and back supports comprising upper and lower links pivoted to the frame and to the back, the upper links being in substantial alinement with the back in the 55 closed position to resist an upward effort, and the lower links being in substantial alinement with the back in the open position to resist a downward effort, and a stop limiting the swing of the back beyond the 60 closed position.

14. In a folding davenport, a frame, a 65 back mounted to swing into open or closed position, and back supports comprising upper and lower links pivoted to the frame and to the back, said links, frame, and back forming a double-toggle joint to resist upward effort when said back is in the closed position, and downward effort when said back is in the open position. 70

Signed at Tacoma, Washington, this 30th day of April, 1915.

ORNAN A. HONSINGER.
